(57) **CLAIM**

The ornamental design for a bottle, as shown and described.

DESCRIPTION

FIG. 1 is a perspective view of a bottle, showing the new design, the broken line showing is for illustrative purposes only, and forms no part of the claimed design;

FIG. 2 is an elevational view thereof;

FIG. 3 is another elevational view thereof, representing a partial rotation of the bottle about its vertical axis from the elevational view depicted in FIG. 2;

FIG. 4 is another elevational view thereof, representing a partial rotation of the bottle about its vertical axis from the elevational view depicted in FIG. 3;

FIG. 5 is another elevational view thereof, representing a partial rotation of the bottle about its vertical axis from the elevational view depicted in FIG. 4;

FIG. 6 is a top plan view thereof; and,

FIG. 7 is a bottom plan view thereof.
